UNITED STATES PATENT OFFICE

ALBERT C. WEIGEL, OF EAST ORANGE, NEW JERSEY, ASSIGNOR TO INTERNATIONAL COMBUSTION ENGINEERING CORPORATION, OF NEW YORK, N. Y., A CORPORATION OF DELAWARE

BOILER

Application filed August 29, 1929. Serial No. 389,111.

This invention relates to improvements in boilers of the cross drum type having vertically spaced banks of substantially horizontal tubes connected at their ends into front and rear headers.

One of the primary objects of my invention is to increase the effectiveness of the lower bank or section of such boilers.

More specifically stated it is an object of 10 my invention to provide an improved arrangement of the tubes of the lower or drop-header sections of boilers of the class described whereby the velocity of the gases across the upper rows of tubes of the lower 15 section may be considerably reduced below the velocity across the lower rows of tubes, thus reducing the average velocity of gases entering the boiler and thereby increasing the effectiveness of the lower section or bank.

20 How the foregoing, together with such other objects and advantages, as may herein-after appear, or are incident to my invention are realized is illustrated in preferred form in the accompanying drawings, wherein—

25 Fig. 1 is a sectional side elevation of a boiler of the cross drum type embodying my invention.

Fig. 2 is a fragmentary cross section taken on the line 2—2 of Fig. 1, and

30 Figs. 3, 4, 5 and 6 are enlarged fragmentary sectional views illustrating modified arrangements of the tubes of the lower section of the boiler.

35 The boiler comprises in general a steam and water drum *a*, an upper section or main bank of substantially horizontal boiler tubes *b*, and a lower bank of substantially horizontal boiler tubes *c*, commonly known as the 40 drop-header section of the boiler.

The main bank *b* is composed of a multiplicity of boiler tubes inclined somewhat from the horizontal and arranged in a plurality of staggered rows, the tubes of each row being 45 relatively closely spaced, say, for example, on 7 inch centers with 4 inch tubes and the rows also being relatively closely spaced, say, for example, on 6 $\frac{3}{4}$ inch centers. The tubes of the bank are connected at one end into the 50 front headers 3 and at their other ends into

the rear headers 4, which headers may be of the sinuous type.

A plurality of downcomer tubes 5 lead from the water space of the drum *a* to the front headers 3 and a plurality of rows of tubes 6 55 lead from the rear headers 4 to the steam space of the drum *a* to deliver steam generated in the boiler to the drum. The drum is provided with a steam outlet 7 and may have a feed water inlet located at any suitable 60 point.

The lower bank or drop header section *c* of the boiler is composed of a plurality of boiler tubes inclined similarly to those of the main bank and arranged in a plurality of 65 rows. The tubes of the rows are connected at one end into the front drop-headers 8 and at their other ends into the rear drop-headers 9, which drop-headers may be of the same form as the headers of the main bank. Tubes 10 connect the front headers 3 and 8 and tubes 11 connect the rear headers 4 and 9.

I am aware that it has been proposed heretofore to provide drop-header sections for boilers, but it has been customary to arrange 75 and space the tubes in the same manner as those of the main bank, i. e., in closely spaced rows and with the tubes of the rows in close spacing. I propose, however, to arrange and space the tubes of the drop header section in 80 a novel manner whereby the section will be made more effective than heretofore.

In the form of my invention illustrated in Figs. 1 and 2 of the drawings, the lower bank *c* is composed of six rows of tubes and the 85 tubes of the two intermediate rows 12 and 13 are relatively closely spaced as are also the rows themselves. The tubes of the two lower rows 14 and 15 and of the two upper rows 16 and 17 are much more widely spaced 90 apart. Also the space between the rows 14, 15 and 16, 17, and the distance these rows are spaced above and below the intermediate rows 12 and 13 is much greater than the space between the rows 12 and 13. 95

By way of example it may be assumed that the tubes of the rows 12 and 13 are spaced on 7 inch centers and those of the rows, 14, 15, 16 and 17 on 14 inch centers. The vertical spacing of the rows 12 and 13 100

may be assumed to be $6\frac{3}{16}$ inches and that of remaining rows $12\frac{3}{8}$ inches. It is pointed out, however, that in some instances it may be desirable to arrange all of the lower 5 rows in close spacing.

In boilers of the type herein involved it is standard practice to arrange the tubes in rows which are spaced approximately $6\frac{3}{16}$ inches apart and to locate the tubes on approximately 10 7 inch centers in the rows, and it will be seen, therefore, that I may obtain my novel arrangement of tubes while still employing standard headers arranged in the 15 usual manner, in which case I omit the usual rows of tubes between the rows 14, 15 and 12, and between the rows 13, 16 and 17. In the rows 14, 15, 16 and 17 I omit alternate tubes so that the spacing of these tubes will be twice the standard spacing. The tube 20 holes in the headers where tubes have been omitted may be plugged if headers having standard spaced holes are employed. However, headers having blank spaces where tubes are to be omitted may be employed.

25 A superheater 18 may be located in the space 19 between the upper and lower banks and suitable baffling such as indicated at 20, 21 and 22 may be provided. The products 30 of combustion leaving the combustion chamber 23 pass upwardly over and among the tubes of the lower bank *c*, then rise through the pass 24, then pass downwardly through the pass 25, then up through the pass 26 and finally pass to the offtake 27.

35 The combustion chamber may be fired in any suitable manner, although I prefer to employ pulverized fuel, and the chamber may be provided with steam evaporating surfaces, such as water tubes 28 and 29, arranged to line walls of the chamber.

In Fig. 3 I have shown a modification of 40 the invention in which the space between the four upper rows of tubes 12*a*, 13*a*, 16*a* and 17*a* is the same, but it is to be noted that alternate tubes are omitted in the two upper 45 rows 16*a* and 17*a*.

In the modification illustrated in Fig. 4 the space between the two upper rows of 50 tubes 16*b* and 17*b* is the same as the space between the two intermediate rows 12*b* and 13*b*, but the space between the rows 13*b* and 16*b* is considerably greater. Alternate tubes are omitted in the two upper rows 16*b* and 17*b*.

55 In Fig. 5 a modification is illustrated in which the rows 12*c*, 13*c* and 16*c* are of like spacing, while the spacing between the rows 16*c* and 17*c* is considerably greater. Here, again, alternate tubes of the upper rows 16*c* and 17*c* are omitted.

The arrangement of the two lower rows of Figs. 3, 4 and 5 may be the same as that of Figs. 1 and 2.

60 In Fig. 6 I have illustrated a modification in which five rows of tubes are employed.

The four upper rows of tubes 12*d*, 13*d*, 16*d* and 17*d* may be arranged in accordance with any of the forms above described and as illustrated the arrangement is the same as Fig. 2. The bottom row of tubes 14*d* is spaced 70 below the row 12*d* a distance approximately equal to twice the spacing of the rows 12*d* and 13*d*. The tubes of the bottom row are spaced on close centers corresponding to the spacing of the tubes of the rows 12*d* and 13*d*. 75

From the foregoing it will be seen that I have provided an arrangement in which the velocity of the gases across the upper rows of tubes of the drop header section *c* will be considerably reduced over standard practice, thereby making the tubes of the section more effective. Furthermore, the average velocity of gases entering the boiler is reduced. In consequence, among other things, the drop header bank is made more effective throughout its length. 80

The arrangement is particularly advantageous in boilers having baffling of the general arrangement illustrated in the drawings, for the reason that, without provision to the contrary, the point of maximum resistance to gas flow in such boilers is at the bottom of the upright baffle 21, due to the fact that the hot gas must pass through an area approximately equal to one-half the length of tubes 90 and of a width equal to the space between the tubes (say three inches in standard practice) 95 times the number of sections.

Through the practice of my invention this area may be increased as much as 66%, for I 100 have cut down the number of tubes in the upper rows of the drop header section. By spreading these upper rows vertically, sufficient room is left for the gases to enter the freer space along practically the full length 105 of the tubes that are close together and then part of the gases can run parallel to the tubes and freely enter the space immediately below the superheater.

The arrangement of the lower rows of 110 tubes prevents choking or substantial restriction in the gas passages.

I claim:—

1. In a boiler having a main section of boiler tubes and a drop-header section of boiler tubes, the combination of upper and lower rows of spaced boiler tubes in the drop header section, the upper rows being spaced more widely apart than lower rows and the spacing of the tubes of the upper rows being greater than the spacing of the tubes of lower rows. 115

2. A boiler including vertically spaced banks of substantially horizontal water tubes and their headers, the lower bank having a plurality of rows of boiler tubes, at least two lower rows of which are closely spaced and composed of a plurality of closely spaced tubes and at least the two top rows of which are relatively widely spaced apart and composed of a plurality of relatively widely 120 125 130 spaced tubes.

spaced tubes, and a super-heater located in the space between the banks of tubes.

3. A boiler including vertically spaced banks of substantially horizontal water tubes and their headers, the lower bank having a plurality of rows of boiler tubes arranged in lower, intermediate and upper groups, the tubes of the intermediate group being relatively closely spaced and the tubes of the lower and upper group being relatively widely spaced.

4. A boiler including vertically spaced banks of substantially horizontal water tubes and their headers, the lower bank having upper and lower rows of spaced boiler tubes, the upper rows being spaced more widely apart than lower rows and the spacing of the tubes of the upper rows being greater than the spacing of the tubes of lower rows.

20 In testimony whereof I have hereunto signed my name.

ALBERT C. WEIGEL.
